MACHINE FOR SHAPING UPPERS OVER LASTS

Filed Aug. 28, 1930

Fig. 2.

INVENTOR
George Goddu
By his Attorney,
Harlow M. Davis

UNITED STATES PATENT OFFICE

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY

MACHINE FOR SHAPING UPPERS OVER LASTS

Application filed August 23, 1930. Serial No. 478,423.

This invention relates to machines for use in the manufacture of shoes for shaping uppers over lasts, and is herein illustrated as applied to a machine for lasting shoes progressively by pulling the upper, laying it inwardly over the insole and fastening it in different locations successively along the edge of the shoe bottom, usually at the opposite sides of the shoe, as the shoe is presented by the operator in different lasting positions, the machine shown having means for fastening the upper to a lip or rib on the insole (hereinafter referred to as the lip). It is to be understood, however, that in its more general aspects the invention is not limited to machines of the particular type illustrated nor to machines for operating upon shoes of that type in which the insole is provided with a lip.

Machines of the above-mentioned character are each provided with a shoe rest against which the operator holds the bottom of the shoe and which supports the shoe against the pull of the gripper on the upper heightwise of the last, this shoe rest also assisting by its engagement with the insole in preventing displacement of the shoe laterally or in a direction transverse to its height by the force applied in pulling or laying the upper inwardly over the insole, but permitting the shoe to be moved readily from one lasting position to another. In operating upon shoes in which the insole has a lip on its outer face, such as welt shoes, the shoe rest engages the inner side of the lip, and accordingly its action in preventing such displacement of the shoe is due largely to its pressure against the lip.

An object of the present invention is to provide improved means for controlling the shoe in machines of the general class referred to, and especially for holding the shoe against displacement by the force applied in pulling or laying the upper inwardly over the shoe bottom. For the purpose in view the construction shown comprises means which is movable intermittently into and out of engagement with the insole in time relation to the successive lasting operations on the shoe and acts in conjunction with the shoe rest to resist the force tending to displace the

shoe as above described. More particularly, this mechanism, as illustrated, comprises a member formed to penetrate the insole and controlled by the gripper-operating lever, so that the member is moved into operative position as the gripper is moved toward the shoe preparatory to the gripping of the upper and is withdrawn from operative position as the gripper is retracted after its release of the upper, thus permitting the shoe to be readily advanced to the next lasting position. It will be evident that as applied to a machine in which the shoe rest engages a lip on the insole as hereinbefore described, such additional shoe-controlling mechanism serves to lessen the strain on the insole lip due to the pressure of the lip against the shoe rest and thus to insure against distortion of the lip or such displacement of the shoe relatively to the shoe rest as to result in improper or insecure fastening of the upper if the lip is formed of unusually flexible or yielding material.

The novel features of the invention will now be more particularly described by reference to the accompanying drawing and thereafter pointed out in the claims.

In the drawing,

Fig. 1 is a view, partly in right-hand side elevation and partly in section, of a portion of a machine in which the invention is embodied;

Fig. 2 shows a portion of the structure in left-hand side elevation;

Fig. 3 is a view illustrating the operation of the machine on a shoe, and

Fig. 4 is a view at right angles to Fig. 2 showing more clearly the shape of the additional shoe-controlling member.

The invention is herein illustrated as applied to a machine constructed as disclosed in Letters Patent No. 1,796,451, granted upon an earlier application of mine on March 17, 1931, and accordingly only such parts of the machine as it is necessary to refer to for an understanding of this invention are herein shown and will be described in detail. The machine includes in its organization a shoe rest 10 which is arranged to engage the bottom of a shoe presented and held by the operator in different positions successively for

the progressive lasting of the shoe along each of its opposite sides. As herein illustrated the shoe rest 10 is constructed and arranged to engage the inner side of the lip *a* of the insole to determine the lateral position of the shoe and also to clinch staples driven as hereinafter described for fastening the upper to the lip of the insole. For pulling the upper the machine is provided with a gripper 12 having a pair of jaws 14 which grip the upper and pull it first heightwise of the last and then inwardly over the insole. As described in detail in the above-mentioned Leiters Patent, the gripper is moved heightwise of the last by a two-part updraw lever comprising a front part 16 connected to the gripper and fulcrumed at 18 on the head of the machine, and a rear part 20 pivoted at 22 on the rear end of the front part 16 and operated by a cam 24 on a cam shaft 26. The two parts of the updraw lever are further yieldingly connected together through a spring 28 so as to permit relative movement between them in response to resistance of the upper to the pull of the gripper thereon. The gripper 12 is pivotally mounted on the front end of the part 16 of the updraw lever for swinging movements inwardly and outwardly over the shoe bottom, these movements being controlled by a rod 30 and a bell-crank lever 32 which is connected to the rod and is operated by a cam 34 on the cam shaft 26. A torsion spring 36 acts on the lever 32 to impart to the gripper movement to pull the upper yieldingly inward over the insole, and the cam 34 moves the gripper in the opposite direction against resistance of the spring.

In operation the gripper is moved downwardly toward the bottom of the shoe by downward movement of the part 16 of the updraw lever and is moved outwardly toward the edge of the shoe bottom by the cam 34 preparatory to the gripping of the upper in each lasting location. Thereafter the gripper is moved upwardly by the updraw lever to pull the upper heightwise of the last, the spring 28 being compressed more or less by reason of resistance of the upper to the pull of the gripper, and is then moved inwardly over the shoe bottom by the spring 36 under control of the cam 34 to pull the upper inwardly over the insole. As the gripper is thus operated to pull the upper inwardly, an overlaying member 38, which in the machine illustrated consists of a staple-guiding nozzle, is moved inwardly over the shoe bottom in a downwardly inclined direction and acts on the upper to lay it over and down upon the insole and against the outer side of the insole lip. Substantially at the end of the inward movement of this member the gripper releases the upper, whereupon the front portion 16 of the updraw lever is swung upwardly by the spring 28

to carry the gripper farther away from the shoe bottom. Thereafter a staple is driven from the member 38 through the upper and the insole lip and is clinched on the shoe rest member 10 to fasten the upper to the lip. 70

It will be evident that as the upper is pulled inwardly over the insole by the gripper and is additionally forced inward by the overlaying member 38, considerable force is applied to the shoe tending to displace it laterally or in a direction transverse to its height. The shoe is normally held against such displacement by engagement of the shoe rest 10 with the lip of the insole and in part also by such friction as there is between the insole and the lower end face of the shoe rest due to the upward pressure of the shoe against the shoe rest as the operator supports and holds the shoe. To assist further in controlling the shoe, and thus to insure against any possibility under some conditions of distortion of the insole lip by too great a strain thereon or of such displacement of the shoe relatively to the shoe rest 80 as to result in the driving of a staple or staples in improper relation to the lip, as well as to relieve the operator of the necessity of exercising any special care in holding the shoe in such manner as to guard against these results, the machine herein shown is provided with a member 40 which is moved intermittently into and out of engagement with the insole in a location near the shoe rest 10 and has sharp prongs adapted to penetrate the insole. The member 40 has an upwardly extending shank portion 42 which is slidably mounted in a bracket 44 fast on one side of a holder 46 to which the shoe rest 10 is secured. The movements of the member 40 toward and from the shoe are effected by the front portion 16 of the updraw lever. For this purpose the upper end of the part 42 is connected by a flexible spring coupling 48 to the lower end of a rod 50 which extends upwardly through an opening formed in a stud 52 carried by the part 16 of the updraw lever. Between the stud 52 and a clamp 54 which is fast on the rod 50 is a spring 56 through which downward movement is imparted yieldingly to the rod 50 by the updraw lever to force the member 40 downwardly into contact with the shoe. Nuts 58 on the upper end of the rod 50 provide means whereby the stud 52 lifts the rod as the part 16 of the lever is moved upwardly, thereby withdrawing the member 40 from engagement with the shoe. It will be understood that the member 40 is thus forced downwardly into contact with the insole as the gripper is moved downwardly toward the shoe bottom preparatory to the gripping of the upper in each lasting location, the spring 56 being compressed more or less during further downward movement of the part 16 of the 90

100

110

120

130

updraw lever after the member 40 has engaged the insole. Thereafter the spring 56 serves to maintain the member 40 yieldingly in its operative position during such upward movement of the part 16 of the lever as takes place in pulling the upper heightwise of the last, and it is only upon release of the upper by the gripper substantially at the end of the operation of laying the upper inwardly over the insole that the member 40 is withdrawn from engagement with the insole by the further upward movement of the part 16 to its starting position. It will thus be seen that during the time that force is applied to the shoe tending to displace it laterally, the member 40 acts conjointly with the shoe rest 10 in holding the shoe against such displacement, and the member is thereafter withdrawn from engagement with the insole to permit the shoe to be readily advanced by the operator to the next lasting position. By its holding action on the shoe the member 40 relieves the insole lip of any excessive strain such as might distort it or result in improper displacement of the shoe if the lip were made of unusually flexible or yielding material, and at the same time relieves the operator of the necessity of exercising as much care as he might otherwise have to exercise under such conditions in holding the shoe in such manner as to guard against excessive strain on the lip.

While the invention is herein illustrated in its application to a machine for operating on shoes in which the upper is fastened to a lip on the insole, with the special object of avoiding excessive strain on the lip, it will be evident that the novel means provided for controlling the shoe is not limited in utility to an organization of that particular character.

Having described the invention, what I claim as new and desire to secure by Letters Patent of the United States is:

1. In a machine of the class described, the combination with means for operating on a shoe successively in different locations along the edge of the shoe bottom to pull the upper and to lay its marginal portion inwardly over the shoe bottom, and a shoe rest arranged to engage the bottom of a shoe presented by the operator in different positions for the different upper-pulling and overlaying operations to hold the shoe against displacement heightwise and laterally by the force applied in those operations, of means movable automatically into and out of position to co-operate with said shoe rest in holding the shoe against lateral displacement by the force applied thereto in operating on the upper in each location.

2. In a machine of the class described, the combination with means for operating on a shoe successively in different locations along the edge of the shoe bottom to pull the upper

and to lay its marginal portion inwardly over the shoe bottom, and a shoe rest arranged to engage the bottom of a shoe presented by the operator in different positions for the different upper-pulling and overlaying operations to hold the shoe against displacement heightwise and laterally by the force applied in those operations, of a device for engaging the bottom of the shoe to co-operate with said shoe rest in holding the shoe against lateral displacement by the force applied thereto in operating on the upper in each location, and automatic means for moving said device into engagement with the bottom of the shoe in time relation to each upper-pulling and overlaying operation and for moving it thereafter out of engagement with the shoe to permit the shoe to be advanced to the next operating position.

3. In a machine of the class described, the combination with means for operating on a shoe on a last successively in different locations along the edge of the shoe bottom to pull the upper heightwise of the last and inwardly over an insole on the last and also to lay the marginal portion of the upper inwardly over the insole, and a shoe rest arranged to engage the insole of a shoe presented by the operator in different positions for the different upper-pulling and overlaying operations to support the shoe against the heightwise pull on the upper and also to hold it against displacement in a direction transverse to its height by the force applied in pulling and laying the upper inwardly over the insole, of means movable automatically into and out of engagement with the insole to co-operate with the shoe rest in holding the shoe against such displacement in each operating position and to release the shoe for movement to the next operating position.

4. In a machine of the class described, the combination with means for operating on a shoe successively in different locations along the edge of the shoe bottom to pull the upper and to lay its marginal portion inwardly over an insole having a lip thereon, and a shoe rest arranged to engage the lip of the insole of a shoe presented by the operator in different positions for the different upper-pulling and overlaying operations to position the shoe and hold it against displacement in a direction transverse to its height by the force applied thereto in operating on the upper, of means movable automatically into and out of position to co-operate with said shoe rest in holding the shoe against such displacement.

5. In a machine of the class described, the combination with means for operating on a shoe successively in different locations along the edge of the shoe bottom to pull the upper and to lay its marginal portion inwardly over an insole having a lip thereon, and a

shoe rest arranged to engage the lip of the insole of a shoe presented by the operator in different positions for the different upper-pulling and overlaying operations to position the shoe and hold it against displacement in a direction transverse to its height by the force applied thereto in operating on the upper, of a device formed to penetrate the insole to co-operate with said shoe rest in holding the shoe against such displacement, and automatic means for moving said device into engagement with the insole in time relation to each upper-pulling and overlaying operation and for moving it thereafter out of engagement with the insole to permit the shoe to be advanced to the next operating position.

6. In a machine of the class described, the combination with means for pulling the upper of a shoe over a last successively in different locations along the edge of the shoe bottom as the shoe is presented in different positions, a member movable to lay the marginal portion of the upper inwardly over an insole on the last and against a lip on the insole in each location, said member being formed to serve as a guide for fastenings driven through the upper and the lip, and a shoe rest arranged to engage the lip of the insole for holding the shoe against displacement in a direction transverse to its height and for clinching the fastenings, of a device movable alternately into and out of position to assist by engagement with the insole in holding the shoe against such displacement by the force applied thereto in operating on the upper in each location.

7. In a machine of the class described, the combination with means for pulling the upper of a shoe over a last successively in different locations along the edge of the shoe bottom, means for laying the marginal portion of the upper inwardly over the shoe bottom in each location, and a shoe rest arranged to engage the bottom of a shoe presented in different positions for the different upper-pulling and overlaying operations, of a device controlled by said upper-pulling means for engaging the shoe to assist in holding it against displacement in a direction transverse to its height by the force applied thereto in operating on the upper in each location.

8. In a machine of the class described, the combination with means for pulling the upper of a shoe over a last successively in different locations along the edge of the shoe bottom, means for laying the marginal portion of the upper inwardly over an insole on the last in each location, and a shoe rest arranged to engage a lip on the insole to position the shoe and hold it against displacement in a direction transverse to its height by the force applied thereto in operating on the upper as the shoe is presented in differ-

ent positions for the different upper-pulling and overlaying operations, of a device controlled by said upper-pulling means for engaging the insole to co-operate with said shoe rest in holding the shoe against such displacement and thereby to prevent excessive strain on the lip of the insole.

9. In a machine of the class described, the combination with means for pulling the upper of a shoe over a last successively in different locations along the edge of the shoe bottom, means for laying the marginal portion of the upper inwardly over the shoe bottom in each location, and a shoe rest arranged to engage the bottom of a shoe presented in different positions for the different upper-pulling and overlaying operations, of a device for engaging the bottom of the shoe to assist in holding the shoe against displacement in a direction transverse to its height by the force applied thereto in operating on the upper in each location, and connections between said device and the upper-pulling means for moving the device into and out of operative position by movements of said upper-pulling means.

10. In a machine of the class described, the combination with a gripper for pulling the upper of a shoe over a last successively in different locations along the edge of the shoe bottom, a lever for operating said gripper, means for laying the marginal portion of the upper inwardly over the shoe bottom in each location, and a shoe rest arranged to engage the bottom of a shoe presented by the operator in different positions for the different upper-pulling and overlaying operations, of a member for engaging the bottom of the shoe to assist in holding the shoe against displacement in a direction transverse to its height by the force applied thereto in operating on the upper in each location, and means connecting said member to the gripper-operating lever for moving the member into and out of operative position by movements of said lever.

11. In a machine of the class described, the combination with a gripper for pulling the upper of a shoe over a last successively in different locations along the edge of the shoe bottom, a lever movable to carry the gripper toward the shoe preparatory to the gripping of the upper in each location and movable thereafter to operate the gripper to pull the upper, means for laying the marginal portion of the upper inwardly over the shoe bottom in each location, and a shoe rest arranged to engage the bottom of a shoe presented by the operator in different positions for the different upper-pulling and overlaying operations, of a member for engaging the bottom of the shoe to assist in holding the shoe against displacement in a direction transverse to its height by the force applied thereto in operating on the upper in each location, and a

yielding connection between said member and the gripper-operating lever for moving the member into engagement with the shoe as the gripper is moved toward the shoe and for thereafter maintaining it in engagement with the shoe during the upper-pulling movement of the gripper.

12. In a machine of the class described, the combination with means for pulling the upper of a shoe over a last successively in different locations along the edge of the shoe bottom as the shoe is presented by the operator in different positions for the different successive operations, of a device controlled by said upper-pulling means and movable into and out of position to hold the shoe against displacement in a direction transverse to its height while the shoe is presented in each position by the operator.

13. In a machine of the class described, the combination with means for pulling the upper of a shoe over a last successively in different locations along the edge of the shoe bottom as the shoe is presented by the operator in different positions for the different successive operations, of a device for engaging the bottom of the shoe to hold it against displacement in a direction transverse to its height, and a connection between said device and the upper-pulling means for moving the device into and out of engagement with the shoe by the movements of said means.

14. In a machine of the class described, the combination with means movable to pull the upper of a shoe over a last, of a device controlled by said upper-pulling means for holding the shoe against displacement in a direction transverse to its height.

15. In a machine of the class described, the combination with means movable to pull the upper of a shoe over a last, of a member formed to penetrate the bottom of the shoe for holding the shoe against displacement in a direction transverse to its height, and connections between said member and the upper-pulling means for moving said member into and out of operative position by movements of said means.

16. In a machine of the class described, the combination with upper-pulling means movable toward and from a shoe on a last for gripping and pulling the shoe upper over the last, of a device for engaging the bottom of the shoe to hold the shoe against displacement in a direction transverse to its height, and mechanism for moving said device into operative position by the movement of the upper-pulling means toward the shoe and for maintaining it in that position during the pulling of the upper.

17. In a machine of the class described, the combination with upper-pulling means movable toward and from a shoe on a last for gripping and pulling the shoe upper over the last, of a device for engaging the bottom of the

shoe to hold the shoe against displacement in a direction transverse to its height, and a yieldable connection between said device and the upper-pulling means for moving the device into operative position by the movement of the upper-pulling means toward the shoe and for thereafter maintaining it in that position until the upper is released by the upper-pulling means.

18. In a machine of the class described, the combination with upper-pulling means movable toward a shoe on a last to grip the shoe upper and movable thereafter reversely to pull the upper and then farther away from the shoe after release of the upper, of a device for engaging the bottom of the shoe to hold the shoe against displacement in a direction transverse to its height, and a connection between said device and the upper-pulling means for moving the device into operative position by the movement of the upper-pulling means toward the shoe and for withdrawing it from that position by the movement of said means away from the shoe after release of the upper.

19. In a machine of the class described, the combination with a gripper for pulling the upper of a shoe over a last, and a lever for operating said gripper to pull the upper, of a device arranged to be moved by said lever into and out of position for holding the shoe against displacement in a direction transverse to its height.

20. In a machine of the class described, the combination with a gripper for pulling the upper of a shoe over a last, and a gripper-operating lever movable toward the shoe preparatory to the gripping of the upper and movable thereafter reversely to pull the upper and then farther away from the shoe after release of the upper by the gripper, of a member for engaging the bottom of the shoe to hold it against displacement in a direction transverse to its height, and means for moving said member into operative position by the movement of said lever toward the shoe, for maintaining it in that position during the pulling of the upper, and for withdrawing it from operative position in response to the movement of the lever away from the shoe after release of the upper.

21. In a machine of the class described, the combination with a gripper for pulling the upper of a shoe over a last, and a lever for operating said gripper, of a shoe-controlling member mounted independently of the gripper for movement into and out of engagement with the bottom of the shoe, and means connecting said member to the gripper-operating lever for operating the member by the movements of said lever.

22. In a machine of the class described, the combination with a gripper for pulling the upper of a shoe over a last, and a lever for operating said gripper, of a shoe-controlling

member mounted independently of the gripper for movement into and out of engagement with the bottom of the shoe, a rod controlled by the gripper-operating lever, a flexible connection between said member and rod, and a spring for transmitting the force of the lever yieldingly to said rod to move said member into engagement with the shoe.

23. In a machine of the class described, the combination with means for pulling the upper of a shoe over a last, of a device movable under control of said upper-pulling means into and out of position to penetrate the bottom of the shoe for controlling the shoe.

24. In a machine of the class described, the combination with means for pulling the upper of a shoe over a last and for laying its marginal portion inwardly over an insole having a lip thereon, and a shoe rest for engaging said lip to hold the shoe against displacement in a direction transverse to its

height by the force applied thereto in operating on the upper, of a member arranged for additional engagement with the insole to assist in holding the shoe against such displacement and thereby to prevent excessive strain on the lip of the insole.

25. In a machine of the class described, the combination with means for pulling the upper of a shoe over a last and for laying its marginal portion inwardly over an insole having a lip thereon, and a shoe rest for engaging said lip to hold the shoe against displacement in a direction transverse to its height by the force applied thereto in operating on the upper, of a member formed and arranged to penetrate the insole to assist in holding the shoe against such displacement.

In testimony whereof I have signed my name to this specification.

GEORGE GODDU.
